Primary Examiner — Rhea Shields(74) *Attorney, Agent, or Firm* — Banner & Witcoff, Ltd.(57) **CLAIM**

The ornamental design for a soap dispenser, as shown and described.

DESCRIPTION

FIG. 1 is a top, front, right perspective view of a soap dispenser showing our new design;

FIG. 2 is a top view thereof;

FIG. 3 is a right side view thereof, wherein the left side view is a mirror image thereof;

FIG. 4 is a front view thereof; and,

FIG. 5 is a rear view thereof.

The broken lines are for the purpose of illustrating unclaimed boundaries or environment only, and form no part of the claimed design.
